UNITED STATES PATENT OFFICE

EZRA L. WHITE, OF BARRE, VERMONT

DESIGN FOR EMBLEMATICAL ORNAMENT OR SIMILAR ARTICLE OF MANUFACTURE

Application filed April 29, 1931. Serial No. 39,656. Term of patent 3½ years.

To all whom it may concern:

Be it known that I, EZRA L. WHITE, a citizen of the United States, residing at Barre, in the county of Washington and State of Vermont, have invented a new original, and ornamental Design for an Emblematical Ornament or Similar Article of Manufacture, of which the following is a specification, reference being had to the accompanying drawings, forming part thereof.

I claim:

The ornamental design for an emblematical ornament or similar article of manufacture, as shown.

In testimony whereof I affix my signature.

EZRA L. WHITE.
